UNITED STATES PATENT OFFICE

JULIUS RITTER, JR., OF RACINE, WISCONSIN, ASSIGNOR TO HARTMANN TRUNK COMPANY, OF RACINE, WISCONSIN, A CORPORATION OF WISCONSIN

WARDROBE CASE

Application filed October 15, 1930. Serial No. 488,714.

This invention relates in general to improvements in the art of manufacturing luggage carrier cases, and relates more specifically to improvements in the construction of joints and connecting elements between the sections constituting the body or housing of wardrobe suitcases or the like.

A general object of the invention is to provide a carrier case which is simple and durable in construction, and which provides an effective and dustproof housing of neat appearance.

Numerous types of wardrobe suitcases and the like, have heretofore been offered to the trade, these cases being so designated because of the fact that they make provision for the storage of wearing apparel of various kinds. Due to the more recent extensive transportation by air, it is necessary to place certain limitations upon the bulk of the baggage, and many of the prior wardrobe cases are decidedly unsuitable for such transportation due to their great size, lack of strength, and general construction.

It is a more specific object of the present invention to provide an improved carrier case which is especially adapted for aerial transportation by virtue of its great strength and compactness.

Another specific object of the invention is to provide an improved dustproof joint between the sections constituting the body of a luggage carrier case, which not only serves to effectively prevent ingress of dust by providing a tight joint, but which also adds strength to the case without adding undesirable weight.

A further specific object of the invention is to provide simple and efficient means for uniting the body sections of a sectional suitcase or the like, and for permitting convenient detachment of the sections.

Still another specific object of the invention is to provide an improved corner construction for luggage carrier cases, whereby a rigid casing structure results.

These and other objects and advantages will appear from the following description.

The present application is a continuation in part of co-pending application Serial

Number 276,673, filed May 10th, 1928, which discloses novel features of valance construction specifically claimed herein. Some of the novel features of wardrobe case corner and edge construction disclosed but not specifically claimed herein, form the subject of co-pending application Serial Number 253,053, filed February 9th, 1929. Some of the novel features of tongue and groove connection between the cover and base sections of a wardrobe suitcase, disclosed but not specifically claimed herein, are disclosed in the co-pending application Serial No. 335,292, filed January 26th, 1929, now Patent No. 1,799,251, April 7, 1931.

A clear conception of embodiments of the several novel features constituting the present invention and of the mode of constructing and of manipulating cases built in accordance therewith, may be had by referring to the drawing accompanying and forming a part of this specification, in which like reference characters designate the same or similar parts in the several views:

Fig. 1 is a central vertical section through an improved wardrobe suitcase having the outer covering omitted therefrom;

Fig. 2 is an enlarged fragmentary sectional view through the improved valance constituting the joint between the sections of the case shown in Fig. 1;

Fig. 3 is an elevation of one of the corners of the case shown in Fig. 1, looking directly into the special corner fitting, the covering having been omitted for the sake of clearness;

Fig. 4 is an enlarged side elevation of the lower portion of the improved case, some of the parts having been broken away and the outer covering having likewise been omitted for the sake of clearness; and

Fig. 5 is a section through the lower portion of the case, the section being taken along the line 5-5 of Fig. 4 and the outer covering having been likewise omitted for the sake of clearness.

The improved wardrobe suitcase specifically shown in the drawing by way of illustration, comprises a body consisting of an L-shaped base section 6 and a cover section 7 cooperating with the base section to provide a

complete housing. The walls and corners of the sections 6, 7 are preferably constructed of ply wood in accordance with the disclosure in said application Serial Number 253,053, in order to provide a light case of maximum strength. The interior of the base section 6 may be provided with a rack and clothes hangers of usual construction, and the cover section 7 which is freely removable from the base section, may be provided with partitions 11 as shown, secured to the walls of this section by means of metal angle brackets and rivets having flat heads which lie flush with the outer surfaces of the section walls.

15 The lower portion of the cover section 7 may also be provided with detachable hinges 22 comprising metal hook portions coacting with metal socket portions as shown in Figs. 1 and 4. These hinges cooperate with extensions or tongues 8 formed integral with the opposite side walls of the cover section 7, and with a suitable lock 10 coacting with the upper ends of the sections 6, 7 remote from the hinges, to maintain the case in closed condition. While the hinges 22 serve to effectively retain the cover section 7 in closed position, they nevertheless permit free removal of the cover section, or separation of the sections, when the cover section 7 has been swung open as shown in Fig. 1. The tongues 8 are adapted to interlock with relatively deep grooves formed at the upper edges of the sides of the horizontal portion of the base section 6, in a manner similar to that shown in said application Serial Number 335,292. In the present case, however, this interlock is obtained by means of Z-shaped metal strips 17 and metal plates 19 co-acting therewith, the plates 19 having integral end flanges 18 cooperable with the inner surface of the cover section to resist inward bending of the main cover wall when the case is closed. The strips 17 and plates 19 are rigidly united and secured to the reinforced upper edges of the base section walls, by means of long rivets 20 having heads which lie flush with the outer surface of the case, as shown in Figs. 4 and 5.

50 The remaining coacting edge portions of the sections 6, 7, remote from the hinges 22, are provided with an improved dustproof valance consisting of a channel or U-shaped metal strip 12 resting upon the edge of the side walls of one of the sections 6, 7 to form an elongated recess or groove 15. While the strip 12 is shown as being attached to the base section, this strip may obviously be attached to the cover section instead, and the strip 12 has a single integral flange co-acting with the inner adjacent surface of its supporting section 6. The edge of the cover section is adapted to enter and to snugly fit the valance groove 15, and the strip 12 is rigidly attached to its supporting section 6 by means of rivets 14, the outer surfaces of

the heads of which likewise lie flush with the outer surface of the case. The metal strip 12 extends around the inner portions of the corners, but is cut away at the outer corner portions as shown in Fig. 3. Metal reinforcing corner pieces 16 are secured to the valance supporting section 6 at the corners, and these corner pieces are held in place by means of rivets 14 as shown in Fig. 1.

70 The entire external surface of the case is protected and concealed by means of a suitable covering 13 which also conceals and covers the strips 12, 17 and the plates 19. The covering extends within the case sections 6, 7 sufficiently to enable the case lining to be brought over the edges thereof. The base section 6 may furthermore be provided with a handle 9 secured to the section by stitching, and the inner flange of the strip 12 may be provided with cut-outs 21 as shown in Fig. 1, in order to permit such attachment of the handle 9 by stitching.

75 By providing the valance with a flange on the inside only of the case, in order to permit attachment thereof to the side walls of the supporting section 6, machine driven rivets 14 may be utilized and the heads of these rivets may be embedded into the wooden walls so as to maintain the outer surface of the case smooth for attachment of the covering 13. 80 If the valance were provided with inner and outer flanges, this would not be permissible and the exterior surface of the case would present an uneven appearance at the place of attachment of the valance. The use of the flanges on opposite sides of the walls would also necessitate the use of solid rivets, and machine driven rivets such as employed with the single flange construction, could not be utilized.

85 The single supporting flange also permits convenient application of the handle 9 by sewing. All that is necessary in order to permit application of parts by sewing through the wooden walls, is to provide the cut-outs 21, whereupon the handle retainers may be applied by stitching directly through these retainers and through the covering 13 and wooden case walls. The use of a double flange construction would necessitate cutting 90 out both the inside and the outside flanges, and the cut-out in the outside flange would produce an uneven appearance of the covering 13.

100 The improved corner construction comprising the corner pieces 16, permits accurate fitting of the valance strip along the sides of the supporting section 6, and the flange on the inside of each corner piece provides a reinforcement which strengthens the corners 110 of the case.

115 The valance construction for receiving the extensions 8 at the opposite sides of the case, likewise materially strengthens the case and prevents distortion of the cover at the hinges 120

22, and spreading of the lower end of the cover section 7. The flanges 18 likewise prevent distortion of the cover section, and it will be apparent that any other type of hinge 5 than that disclosed, may be utilized between the sections 6, 7.

The improved valance construction not only eliminates possible ingress of dust, but also materially enhances the rigidity of the 10 case, without undesirably increasing the weight thereof. Cases provided with this type of valance construction present an extremely neat appearance by virtue of the fact that the cover 13 lies smooth and is not 15 bulged and caused to lie uneven by the use of outwardly projecting rivet heads and valance attaching flanges.

It should be understood that it is not desired to limit the invention to the exact 20 details of construction herein shown and described, for various modifications within the scope of the claims may occur to persons skilled in the art.

It is claimed and desired to secure by Letters Patent:

1. In a carrier case, body and cover sections formed of non-metallic sheet material, a metal channel supported by one of said sections and forming an elongated recess 30 extending along an edge of said section and adapted to receive the edge of the other section, said channel having an integral locally interrupted flange secured to the inner surface of the wall of said supporting section, 35 and a handle having retainers secured to said supporting section within the interruptions in said flange.

2. In a carrier case, body and cover sections formed of non-metallic sheet material, a metal channel supported by one of said sections and forming an elongated recess extending along an edge of said section and adapted to receive the edge of the other section, said channel having an integral locally interrupted flange secured to the inner surface of the wall of said supporting section, a covering for the outer surface of said wall and for 45 said channel, and a handle having retainers sewed to said supporting section and to said 50 covering within the interruptions in said flange.

3. In a carrier case, a base section having a lateral extension, Z-shaped strips coacting with the upper side edges of said extension, 55 plates cooperating with said strips within said base section to form recesses, and a cover section having integral projections cooperative with said grooves to retain said cover section in closed position relative to said base 60 section.

4. In a carrier case, a base section formed of non-metallic sheet material and having a lateral extension provided with side walls and an end wall connecting said side walls, 65 a metal plate secured to the inner surface of

each of said non-metallic side walls and projecting beyond the edge thereof, each of said plates having an end projection extending along the inner surface of said connecting wall, means coacting with said plates to form 70 grooves extending along the upper edges of said side walls, and a cover section coacting with said grooves and with said projections.

5. In a carrier case, a base section having a lateral extension provided with side walls 75 and an end wall rigidly uniting said side walls, a Z-shaped strip coacting with the upper edge of each of said side walls, a plate secured to the inner surface of each of said side walls and coacting with the adjacent 80 strip to form a groove along the adjacent side wall edge, each of said plates having an end projection extending along the inner surface of said connecting wall, and a cover section 85 having integral tongues cooperable with said grooves and having a wall connecting said tongues cooperable with said projections.

6. In a carrier case, a base section having a lateral extension provided with side walls 90 and an end wall connecting said side walls, a Z-shaped strip coacting with the upper edge 95 of each of said side walls, a plate cooperating with each of said strips to form a groove, each of said plates having an end projection extending along said end wall, a cover having side walls provided with tongues adapted to coact with said grooves and having another wall connecting said tongued side walls, and a separable hinge coacting with 100 said base and cover section connecting walls.

7. In a carrier case, a base section having side walls and a connecting wall formed of non-metallic sheet material, metal plates secured to said side walls and having projections extending along said connecting wall, means coacting with said plates to form 105 grooves extending along the upper edges of said side walls, a cover having tongues coacting with said grooves and having a wall connecting said tongues and coacting with said projections, and a separable hinge adapted to unite said base and cover section connecting walls.

In testimony whereof, I affix my signature.
